CLAIM

The ornamental design for jewelry, as shown and described.

DESCRIPTION

FIG. 1 is a top-front-right perspective view of a jewelry piece showing my new design;

FIG. 2 is a top-rear-left perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left-side elevational view thereof;

FIG. 8 is a right-side elevational view thereof;

FIG. 9 is an exploded top-front-right perspective view thereof; and,

FIG. 10 is an exploded bottom-front-right perspective view thereof.

The broken lines showing of a center piece of jewelry in FIGS. 1-4 and 9-10 are included for the purpose of illustrating environmental structure and form no part of the claimed design.
